UNITED STATES PATENT OFFICE.

GEORGE W. FISH, OF PECATONICA, ILLINOIS.

BUTTON-FASTENING.

SPECIFICATION forming part of Letters Patent No. 296,155, dated April 1, 1884.

Application filed September 29, 1883. (No model.)

To all whom it may concern:

Be it known that I, GEORGE W. FISH, a citizen of the United States, residing in Pecatonica, in the county of Winnebago and State 5 of Illinois, have invented a new and useful Improvement in Button-Fastenings, of which the following is a specification.

This invention relates to fixing to boxes and packages samples of the goods contained 10 therein; and it consists of a metallic fastening, produced in spider or star form preferably from suitable plate material, having arms to enter or pass through the walls of the package and clinch or bend on its inner face to fix 15 it in place, and other arms capable of being readily bent over the sample of the goods placed in position on the fastening, all of which will be hereinafter more fully described.

In the accompanying drawings, Figure 1 is 20 an isometrical representation of a box produced from paper or other suitable material, substantially such as are employed to contain cards of buttons. Fig. 2 is a card of buttons. Fig. 3 is a spider or star formed metallic fastening. Fig. 4 is a central section cut through 25 the center of the button fixed in place. Fig. 5 is an inner face view, showing the bent or clinched ends of the spider-arms.

In the figures, A represents the metallic fastening, which is produced from plate material 30 in spider or star form, in this instance consisting of a center, a, of circular form in plan. From this circular center radiate pointed arms b, of any suitable length or width.

At c are represented other pointed arms, 35 which radiate from the circular center a on the sides thereof opposite the longer arms b. These arms, in this instance, are of a less length than the arms b. The circular center 40 a of this spider is produced with an elongated opening, d, for a purpose to be hereinafter described. This spider is placed on the box in position to receive the sample, in which position it is fixed by bending either the long

45 or short set of the spider-arms to one side, at a right angle to the plane of its central portion, and then passing the bent arms through the wall of the box, and bending their projecting ends, to clinch them inward toward 50 each other or outward from each other, in the manner shown in Figs. 4 and 5. After this spider is fixed in position, the button B is then placed centrally over the central portion, a, of the spider, and the pointed arms

thereof are then bent upward over the edge 55 portion of the button, which serves to fix it in place, as shown in Fig. 1.

In the employment of my improved fastening for buttons having an eye-loop projecting from their under face, the eye-loop is passed 60 through the central elongated opening, d, as shown in Fig. 4, after which the pointed arms are bent upward over the outer edge portion of the button in the same manner as hereinbefore described, and shown in Figs. 1 65 and 4.

At C is represented a card, to which the buttons e are fixed by means of my improved fastening.

In the foregoing I have shown and described 70 my improvement in connection with buttons, and with button packages, boxes, or cards, to which it is especially adapted, but do not wish to confine its use to this particular purpose, as it is evident that it is capable of use 75 in fixing samples of various kinds of goods to the boxes, cases, packages, or parcels containing them, or to fix the goods to cards.

The application of my improved fastening extends through an almost endless variety of 80 light and valuable trinkets, including flowers—natural or artificial—jewelry, mathematical, surgical, dental, or artificer's instruments, light and fancy cutlery, including light 85 articles in hardware, and also articles useful and ornamental in perhaps most of the known arts.

In preparing boxes, cases, cards, or other articles to contain goods with samples fixed thereto, or the goods fixed in place thereon, 90 the fastenings are usually fixed to the boxes, cases, cards, or other articles in their manufacture, and the boxes, cases, packages, or other articles are furnished to the trade with the fasteners in place thereon; but the fasteners are also to be furnished to the trade in all 95 suitable varieties.

I claim as my invention—

The herein-described button-fastening, of 100 spider or star form, having the central opening, and the long and short radiating arms for fixing buttons of various sizes to their respective packages or to sampling-cards, substantially as specified.

GEORGE W. FISH.
